MEASURING VALVE

Aaron J. Jennings, Battle Creek, Mich., assignor,
by mesne assignments, to The Farval Corporation,
Cleveland, Ohio, a corporation of Ohio

Application June 21, 1930, Serial No. 462,765

4 Claims. (Cl. 184—7)

The present invention pertains to a novel measuring valve designed particularly for use in lubricating systems, although equally useful in other applications where a measured quantity of fluid is to be discharged.

The principal object of the invention is to provide a simple and effective device of this type characterized by the absence of springs such as are commonly used in measuring valves. The movable parts of the device constituting the present invention consists merely of a piston and a double valve slidably mounted in appropriate cavities formed in the valve body. These parts are pressure actuated and are so related in the device that a measured charge of fluid is alternately admitted and discharged.

The invention is fully disclosed by way of example in the following description and in the accompanying drawing, in which—

20 Figure 1 is a longitudinal section of the device;
Figure 2 is a similar section of the device in another position;
Figure 3 is an end view; and

25 Figure 4 is a longitudinal section of a modified construction.

Reference to these views will now be had by use of like characters which are employed to designate the corresponding parts throughout.

In assembling the valve body, there is provided a main cylinder 1 in which is drilled a measuring chamber 2 of suitable size and a passage 3 adjacent thereto, preferably in parallel relation. End caps 4 and 5 are then secured to the ends of the cylinder to close the same. The end caps are previously drilled at 6 at right angles to the cylinder and formed respectively with branches 7 which connect the lines 6 to the passage 3. This system now forms a continuous passage which will hereinafter be called a passage. It will also be seen that the branches 7 are of smaller diameter than the central portion 3 of the passage, whereby valve seats 8 and 9 are formed at the ends of this portion.

The free ends 10 of the passage are adapted for 45 the admission of fluid thereto and are therefore identified merely as intake means in the remainder of the description and in the claims. A nipple 11 extends from the central portion 3 of the passage and constitutes the discharge means.

50 The measuring chamber 2 has a piston 12 slidably therein from end to end and carrying spacers 13 at opposite sides and adapted to engage the members 4 and 5 to retain the major portion of the piston spaced therefrom when the piston is in extreme positions. Ports 14 and 15 connect the

passage 3 to the chamber 2 at opposite sides of the piston and are preferably located directly adjacent the end members 4 and 5 respectively.

In the enlarged portion 3 of the passage is provided a valve structure consisting preferably of a valve stem 16 carrying heads 17 and 18 at its ends. The valve heads are so related to the seats 8 and 9 and ports 14 and 15 as to obstruct the passage alternately at said seats; while the port 14 or 15 at the closed seat is open to the discharge 10 means 11 and the other port closed to the discharge means.

Lines 19 and 20 for supplying fluid under pressure are connected to the inlet means 10 at the ends of the passage in the end members 4 and 5 respectively. The corresponding intake means of a plurality of valves may obviously be coupled into the respective lines 19 and 20.

In the operation of the device, let it be assumed that the line 20 is first opened to admit fluid 20 under pressure into the intake means formed in the end member 5. The pressure moves the double valve towards the other end member 4, as shown in Fig. 1, whereupon the head 17 obstructs the passage at the seat 8 and leaves the chamber 2 open through the port 15 to the operative intake means. Fluid under pressure thus enters the chamber 2, moving the piston also against the opposite end member 4. The volume available in the chamber at the present intake side constitutes the measuring volume. When this space is filled, the line 20 is closed.

On the next operation, the line 19 is opened, whereupon the valve structure moves towards the opposite end member 5 as shown in Fig. 2. In this position the head 18 closes against the seat 9, thereby closing the filled chamber to the inoperative intake means in the member 5. At the same time, the portion of the chamber 2 directly adjacent the port 14 is opened through this port to the operative intake means. The flow of pressure fluid through this path moves the piston towards the opposite end member 5. By the seating of the head 18, the previously filled side of the chamber 2 is opened through the port 15 to the discharge means 11, while the other head 17 has closed the operative intake means to the discharge means. The aforementioned movement of the piston therefore expels the previously measured charge through the port 15, passage 3 and discharge means 11 into the bearing or other device to which the discharge means may be connected. During this operation, the chamber is filled at the side receiving the pressure fluid, whereby a measured charge is provided for 55

discharge in a similar manner when the device is again operated from the other intake means.

In Fig. 4 is illustrated a modification wherein the central portion 23 of the passage may be of the same diameter as the other parts in the end members 24 and 25. It will be evident that the passage section 3 of Figs. 1 and 2 must be of the same diameter as the valve seats 17 and 18 in order to permit insertion of the double valve member. The ends of the section 23 are enlarged at 26 and 27. In order to permit insertion of the valve heads, the valve structure is comprised of two parts comprising heads 28 and 29 in the enlarged portions 26 and 27 respectively and stems 30 and 31 extending from the heads into the passage section 23 but fitting loosely therein. Because of this arrangement, the stems may be inserted separately from opposite ends of the passage section 23. The free ends of the stems abut each other, and the stems function as if they were a single member provided with valve heads at the ends as in Figs. 1 and 2.

Although specific embodiments of the invention have been illustrated and described, it will be apparent that various alterations in the details of construction may be made without departing from the scope of the invention as indicated by the appended claims.

3. What I claim is:—

1. In a measuring valve, a valve body having a measuring chamber and a passage adjacent thereto, an intake means at each end of said passage and adapted for the establishment of unequal pressures simultaneously therein, and discharge means intermediate said ends, a piston slideable in said chamber, ports connecting said passage to said chamber at opposite sides of said piston, valve heads slideable in said passage, the intermediate portion of said passage being of less diameter than its end portions, shoulders between said intermediate portion and the end portion of said passage for the abutment of the inner faces of said heads, spacing means between said heads and extending through the intermediate portion of said passage, said heads being adapted, by greater intake pressure in one of said intake means, to open said means to one of said ports and to close the other intake means to the other of said ports, and to open the latter port to said discharge means.

2. In a measuring valve, a valve body having a measuring chamber and a passage adjacent thereto, an intake means at each end of said passage and adapted for the establishment of unequal pressures simultaneously therein, and discharge means intermediate said ends, a piston slideable in said chamber, ports connecting said passage to said chamber at opposite sides of said piston, valve heads slideable in said passage, the intermediate portion of said passage being of

less diameter than its end portions, shoulders between said intermediate portion and the end portion of said passage for the abutment of the inner faces of said heads, separable spacing means between said heads and extending through the intermediate portion of said passage, said heads being adapted, by greater intake pressure in one of said intake means, to open said means to one of said ports and to close the other intake means to the other of said ports, and to open the latter port to said discharge means.

3. In a measuring valve, a valve body having a measuring chamber and a passage adjacent thereto, an intake means at each end of said passage and adapted for the establishment of unequal pressures simultaneously therein, and discharge means intermediate said ends, a piston slideable in said chamber, ports connecting said passage to said chamber at opposite sides of said piston, valve heads slideable in said passage, the intermediate portion of said passage being of less diameter than its end portions, shoulders between said intermediate portion and the end portion of said passage for the abutment of the inner faces of said heads, separate stem portions on said heads, said stem portions extending into the intermediate portion of said passage and having their inner ends in abutting relationship, said heads being adapted by greater intake pressure in one of said intake means, to open said means to one of said ports and to close the other intake means to the other of said ports, and to open the latter port to said discharge means.

4. A feeder for lubricating bearings comprising an outer casing, a measuring chamber, a piston adapted to reciprocate in said measuring chamber, a valve chamber having two inlet ports adapted for fluid connection with two sources of lubricant supply, communicating passageways between said valve chamber and each end of said measuring chamber, an outlet port communicating with said valve chamber and adapted to be connected to a bearing, a valve controlled by lubricant under greater pressure entering one of said inlet ports adapted to close the other inlet port and to direct lubricant into said measuring chamber on one side of its piston and to force said piston to discharge lubricant from said measuring chamber on the other side of said piston and to said outlet port, said valve comprising dual heads adapted to open and close said inlet ports, shoulders positioned in said valve chamber, the inner faces of said heads being adapted to abut said shoulders when the corresponding valve head is in a position to open its inlet port, and separate stem portions on said heads, said stem portions having their inner ends in abutting relationship.
